MOVABLE RADIATING AND COMBUSTION CHAMBER FOR FLUID FUEL BURNERS

Filed July 11, 1941

UNITED STATES PATENT OFFICE

2,326,432

MOVABLE RADIATING AND COMBUSTION CHAMBER FOR FLUID FUEL BURNERS

James L. Breese, Santa Fe, N. Mex., assignor to
Oil Devices, Santa Fe, N. Mex., a limited partnership of Illinois

Application July 11, 1941, Serial No. 401,920

4 Claims. (Cl. 126—94)

My invention relates to an improvement in heaters and has for one purpose the provision of an improved combustion or radiating drum or member, applicable for example to pot type oil burners.

Another purpose is to provide a radiating member which may readily be tilted to give access to the burner.

Another purpose is to provide such a member which can readily be removed.

Another purpose is to provide such a member which shall gravitally seal itself in relation to the burner and also in relation to the flue when it is in operating position.

Other purposes will appear from time to time in the course of the specification and claims.

I illustrate my invention more or less diagrammatically in the accompanying drawing wherein:

Fig. 1 is a vertical section;

Fig. 2 is a section on the line 2—2 of Fig. 1;

Fig. 3 is a partial vertical section on an enlarged scale; and

Fig. 4 is a section on the line 4—4 of Fig. 3.

Like parts are indicated by like symbols throughout the specification and drawing.

Referring to the drawing, I generally indicate a base member, herein shown in the form of a drum, having a plurality of supporting elements or legs 2 and a bottom 3, with an air inlet aperture 4. Mounted within the member 1 is a burner pot 5, having an upwardly concave bottom 6, liquid fuel inlet means 7, and any suitable means 8 for controlling the flow of liquid fuel to the burner. It will be understood that any suitable control means may be employed, whether automatic or manually operated. I may, for example, use a conventional float chamber.

The drum 6 is provided with a plurality of primary air inlet apertures 9, herein shown as arranged in horizontal rows at different levels. Any suitable means may be employed for admitting secondary air at or near the top of the bottom. I illustrate, for example, a plurality of larger and more closely spaced air inlets 10.

The pot may be supported, for example, upon a flange or angle ring 11, extending inwardly from the base 1, and receiving a top flange 12 outwardly extending from the upper edge of the pot. 13 is any suitable fire ring or upper baffle having a central aperture 14. 15 is a hinge bracket upwardly extending adjacent one edge of the top of the base 1. Extending from the opposite side of the base is a large bracket or structure 16, the upper end of which is secured to any suitable flue member 17. It will be observed that the member 16, at

the top, has a circumferential flange 18, and is provided with any suitable packing 19 of asbestos or the like. As will be clear from Fig. 3, an asbestos packing 20 may be superposed upon the fire ring 13.

21 is a combustion drum or radiating element, which may be hinged to the bracket 15. I provide for example a pocket 22, adapted to receive the upper end of a hinge member 23, pivoted to

10 the bracket 15, as at 24. It will be observed that the member 22 is of such height in relation to the member 23 that, when the drum 21 is resting in position, with its lower flange 25 upon the packing 20, the member 23 is out of contact with the top of the pocket 22, whereby the weight of the drum is effective gravitally to seal the drum against the packing 20. In other words, I provide a sliding connection between the hinge member 23 and the drum 21. The structure has the 15 further advantage that, if desired, this sliding connection may be employed to permit the complete removal of the drum 21 by being merely lifted upwardly away from the base 1 and the hinge structure.

25 The drum 21 is provided with a closed top 26 and a flue connection 27 adapted to engage with its terminal flange 28 the packing 19 associated with the flue 17. It will be understood that the parts are so proportioned that, when the drum 21 is in the full line position of Fig. 1, it is gravitally held, not only against the packing 20, but against the packing 19, whereby the drum is sufficiently tightly sealed from the atmosphere to permit efficient operation. The packing 20 may be omitted, if desired, as shown in Figs. 1 and 2.

30 Any suitable observation window 35 may be employed in the drum, the details of which do not form part of the present invention.

35 It will be realized that, whereas I have described and illustrated a practical and operative device, nevertheless many changes may be made in the size, shape, number and disposition of parts without departing from the spirit of my invention. I therefore wish my description and drawing to be taken as in a broad sense illustrative or diagrammatic, rather than as limiting me to my precise showing.

The use and operation of my invention are as follows:

40 50 No matter how perfect may be the construction of a pot type burner, there are circumstances under which carbon may form. In other words, a pot type burner for liquid hydrocarbons needs to be cleaned from time to time. Also, in lighting such burners, it is customary to drop matches or

burning paper upon the bottom 6 of the burner. It is desirable to have ready access to the burner, both for cleaning and if desired for starting.

In the present structure, if desired, the observation window or door 35 may be completely closed. In that event, in starting the burner, the operator may slightly tilt the drum 21 forwardly to or toward the dotted line position of Fig. 1. The lighted match or piece of paper can then be dropped to the bottom of the pot to ignite the oil delivered through the inlet 7. As soon as the lighted material has been dropped in, the drum can be returned to the full line position, where it will seal itself adequately by gravity.

On the other hand, to get access to the interior of the burner to clean any part thereof, the drum 21 can be tilted forwardly and can then be lifted upwardly from the hinge structure and entirely removed from the heater structure. Thus, the user can observe, clean or repair both the burner pot and the drum with a minimum of delay and with a complete freedom from the necessity of releasing any connections.

As is clear for example from Fig. 1, the bracket or support 16 extends partly around the rear of the burner and is adapted to serve as a shield for projecting heat forwardly into the room and protecting the wall or fuel tank or any other member which is located on the opposite side of the member 16 from the burner.

I claim:

1. In a heater, a base, a pot type burner located in said base, means extending into said base for delivering a liquid fuel into the bottom of said pot, said base including means for directing air to said pot, a flame ring on said base adapted partially to close the top of said pot, a combustion drum mounted on said base, and removable supporting means therefor, including a hinge element fixed in relation to the base, a hinge element pivoted on said fixed hinge element for rotation about a generally horizontal axis, said combustion drum being slidably mounted on said pivoted hinge element, whereby it may be entirely withdrawn therefrom.

2. In a heater, a base, a pot type burner located in said base, means extending into said base for delivering a liquid fuel into the bottom

of said pot, said base including means for directing air to said pot, a flame ring on said base adapted to partially close the top of said pot, a combustion drum mounted on said base, and removable supporting means therefor, including a hinge element fixed in relation to the base, a hinge element pivoted on said fixed hinge element for rotation about a generally horizontal axis, said combustion drum being slidably mounted on said pivoted hinge element, whereby it may be entirely withdrawn therefrom, and packing means at the top of said flame ring, the slidable connection between said pivoted hinge element and the drum permitting the drum to rest freely gravitally upon said packing means.

3. In a heater, a base, a pot type burner located in said base, means extending into said base for delivering a liquid fuel into the bottom of said pot, said base including means for directing air to said pot, a flame ring on said base adapted to partially close the top of said pot, a combustion drum mounted on said base, and removable supporting means therefor, including a hinge element fixed in relation to the base, a hinge element pivoted on said fixed hinge element for rotation about a generally horizontal axis, said combustion drum being slidably mounted on said pivoted hinge element, whereby it may be entirely withdrawn therefrom, a shield element of substantial width mounted upon and upwardly extending from said base, a flue positioned upon said shield element, and a flue connection upon said drum adapted to engage and cooperate with said flue when the drum is in upright position.

4. In a heater, a base, a pot type burner located in said base, means extending into said base for delivering a liquid fuel into the bottom of said pot, said base including means for directing air to said pot, a flame ring on said base adapted to partially close the top of said pot, a combustion drum, a hinge on said base, a movable connection between said drum and said hinge, a combined flue support and shield fixed upon and extending upwardly from said base, a flue mounted thereon, and a flue connection on said combustion drum adapted to engage and cooperate with the flue mounted upon said shield.

JAMES L. BREESE.
